Harald R. Hoffmann, Cleveland, Ohio, assignor to The
M.T. & D. Company, a corporation of Ohio

Filed Feb. 20, 1964, Ser. No. 78,714

Term of patent 14 years

(Cl. D34—15)

In FIGURES 2 and 3 the front portions of the velocipede shown in broken lines in FIGURE 1 have been omitted for convenience of illustration.

The dominant portions of my design are shown in solid lines.

I claim:

The ornamental design for a velocipede, substantially as shown and described.
